UNITED STATES PATENT OFFICE.

WALTER LAMBERT, OF SUNNYSIDE, WASHINGTON

ELECTRIC PUMP.

No. 853,806.

Specification of Letters Patent.

Patented May 14, 1907.

Application filed October 3, 1906. Serial No. 337,229.

To all whom it may concern:

Be it known that I, WALTER LAMBERT, a citizen of the United States, and a resident of Sunnyside, in the county of Yakima and State of Washington, have invented a new and Improved Electric Pump, of which the following is a full, clear, and exact description.

My invention relates to pumping mechanism, and more particularly to electric machinery used for actuating a pump.

My invention further relates to means for automatically throwing both the pump and the electric mechanism out of action when the water in the tank reaches a predetermined level.

Reference is to be had to the accompanying drawings forming a part of this specification, in which similar characters of reference indicate corresponding parts in all the figures.

Figure 1 is a diagrammatic side elevation showing the general arrangement of the pump and the electric mechanism, together with the tank, a portion of which is removed; Fig. 2 is a central vertical section through the solenoid and certain parts connected therewith, showing the movable core, means for mounting the same, the contact mechanism, and the electrical connections for the latter; Fig. 3 is an enlarged side elevation showing the contact mechanism intermediate of the two spools of the solenoid; Fig. 4 is an enlarged section upon the line 4—4 of Fig. 2, looking in the direction of the arrow, and showing the contact rocking lever and its accompanying parts for opening and closing the circuit; and Fig. 5 is a fragmentary plan view of one of the adjusting collars for controlling the stroke of the solenoid core, and showing also the means for adjusting this collar.

A dynamo is shown at 6, a reciprocating pump at 7, a water tank at 8, and a solenoid casing at 9. The water supply comes through the pipe 10 and is passed by the pump 7 through pipes 11, 12 and 13 into the tank 8. Mounted within the upper portion of this tank is a float 14 secured to a contact lever 15. Normally engaging the outer or free end of this lever is a contact point 16, and connected with the latter is a wire 17. This wire leads to a fuse 19 which is connected by a wire 20 with a binding post 20^a. A wire 21 is connected with another binding post 21^a and with the dynamo 6. A slide

rod 22 is disposed coaxially with the casing 9, and mounted rigidly upon this slide rod is a core 23 of magnetic material, such, for instance, as soft iron.

Collars 24, 25 neatly encircle the core 23 and are provided with leather disks 26, 27 or equivalent wearing surfaces, whereby the collars are prevented from undue wear and abrasion. Stirrups 28, 29 are integral with the collars 24, 25, and are provided with cylindrical barrels 30, 31 having pins 32, 33, 34 mounted therein for the purpose of holding the barrels 31 in definite predetermined positions upon the guide rod. The latter is provided with holes 35, 36, the holes 35 being disposed intermediate of the holes 36 and in a different plane as will be understood from Fig. 5. The purpose of this arrangement is to make a strong and reliable connection between the barrels 31 and the guide rod 22. By removing the pins the relative position of the barrels to each other and to the guide rod 22 may be changed at will. In this way the adjusting collars 24, 25 may be spaced at predetermined distances from each other for the purpose of regulating the stroke of the core 23 and the guide rod 22. A cylinder 37 of non-magnetic material, preferably brass, serves as a spool body and is mounted stationary within the casing 9. Encircling the cylinder 37 is a sheet 38 of insulating material, and encircling this is a winding 39. Similarly another cylinder 40 is provided with a sheet 41 of insulating material, and encircling this is a winding 42. The cylinder 40 is provided with a circular head 43, the cylinder 37 having a similar head 44. The heads 43 and 44 are connected by a metallic bridge 45. A contact arm 46 is mounted upon this bridge 45 by means of a pivot 47, and upon opposite sides of the contact arm 46 are contact points 48, 49. When the contact arm is rocked back and forth it successively makes and breaks contact with each of the contact points 48 and 49. Another bridge 50 connects together the heads 43, 44. The bridge 50 is provided with leaves 51 secured to the heads 43, 44 by means of bolts 52. The bridge 45 is provided with leaves 53, the latter being secured by bolts 54. Another bridge 55 is used merely as a strengthening and spacing member for holding the heads 43 and 44. The winding 39 is connected by a wire 56 with the contact point 49, while a wire 57 connects the opposite con-

tact point 48 with the winding 42. Connecting the binding post 21^a with the rocking arm 46 is a wire 58. The binding post 20^a is connected by wires 59, 60 with the windings 39, 42.

My invention is used as follows:—The adjusting collars 24, 25 being spaced apart a suitable distance relatively to each other for the purpose of determining the stroke of the core 23, and consequently the stroke of the pump 7, the dynamo 6 is next thrown into action. The contact lever 15 resting upon the contact point 16 closes that part of the circuit shown in the upper right hand portion of Fig. 1. The completion of the circuit is effected by movements of the rocking arm 46 and this member is at all times in contact with the one or the other of the contact members 48, 49. Supposing it to be in contact with the contact member 48 as indicated in Fig. 3, the circuit is completed as follows:—dynamo 6, wire 18, contact lever 15, contact point 16, wire 17, fuse 19, wire 20, binding post 20^a, wire 60, winding 42, wire 57, contact member 48, contact arm 46, wire 58, binding post 21^a, wire 21 back to dynamo 6. This energizes the winding 42 and the latter draws the core 23 to the left, thereby causing one stroke of the pump 7. The leather disk 26 of the collar 24 now pushes the contact arm 46 to the left, breaking connection between the contact arm 46 and the contact point 48 and making connection between the contact arm and the contact point 49. The circuit is again completed as follows:—dynamo 6, wire 18, contact lever 15, contact point 16, wire 17, fuse 19, wire 20, binding post 20^a, wire 59, winding 39, wire 56, contact member 49, contact arm 46, wire 58, binding post 21^a and wire 21 back to dynamo 6. This energizes the winding 39 and causes the core 23 to move to the right according to Fig. 2, and consequently causes the contact arm 46 to be thrown to the right according to Fig. 3. This completes the circuit first above traced, and this causes a reverse movement, the action being continuous. When the water within the tank 8 reaches a proper height the float 14 is lifted and this automatically breaks connection between the contact lever 15 and the contact point 16. As soon, however, as the water within the tank 8 reaches a level sufficiently low to allow the contact lever 15 to again engage the contact member 16, the circuit is automatically closed and remains closed until opened again by the increased supply

of water. The water within the tank 8 is thus kept approximately at a common level.

Having thus described my invention, I claim as new and desire to secure by Letters Patent:

1. In a device of the class described, the combination of two solenoids arranged in alinement, a core common to both the solenoids and movable longitudinally thereof, oppositely arranged bridges between the adjacent ends of the solenoids, a lever pivoted to one of said bridges, and having its other end resting upon the other bridge, an electric circuit, means whereby the movement of the free end of the lever between the solenoids will connect the current to and from said solenoids in alternation, and means on the core for engaging the lever whereby to move the same.

2. The combination of a slide rod, a core of magnetic material mounted thereupon and movable therewith, collars encircling said core, means for adjusting said collars relatively to said core; a plurality of magnetic members to be energized periodically and alternately for the purpose of attracting said core, contact mechanism for completing and breaking a circuit through said magnetic members, said contact mechanism being provided with a movable member disposed within the path of said collars, and a source of electricity for energizing said magnetic members.

3. The combination of a casing, a pair of solenoids mounted therein and in alinement with each other, a core of magnetic material concentric to said solenoids, a slide rod connected with said core and adapted to reciprocate when actuated thereby, collars encircling said core and provided with portions engaging said slide rod, means for adjusting said last-mentioned portions relatively to said slide rod for the purpose of controlling the relative positions of said collars, and contact mechanism connected with said solenoids for the purpose of energizing the same, said contact mechanism being provided with a movable member disposed within the path of said collars.

In testimony whereof I have signed my name to this specification in the presence of two subscribing witnesses:
